UNITED STATES PATENT OFFICE.

LOTTA A. YOST, OF PHILADELPHIA, PENNSYLVANIA.

LADY'S OR CHILD'S HOSE-SUPPORTER.

SPECIFICATION forming part of Letters Patent No. 733,927, dated July 14, 1903.

Application filed October 17, 1902. Serial No. 127,704. (No model.)

To all whom it may concern:

Be it known that I, Lotta A. Yost, a citizen of the United States, residing in the city and county of Philadelphia, State of Pennsylvania, have invented a new and useful Improvement in Ladies' or Children's Hose-Supporters, of which the following is a specification.

This invention relates to that class of stocking-supporters which support the stocking by connecting it to some portion of the upper garments or to a belt passing around the waist of the wearer.

It is the object of the present invention to overcome the present objectionable features in hose-supporters and to produce a stocking-supporter which will be more comfortable and convenient for the wearer than those heretofore in use and also to so simplify the construction as to lessen the cost of production and at the same time provide an article which is more certain and reliable in its operation.

A further object of my invention is to provide a novel means for readily disconnecting the main strap and the adjusting device from the safety-pin connection, whereby I am enabled to permit the safety-pin to remain permanently attached to the corset or other portion of the wearer's apparel, so that the necessity for fastening and unfastening said safety-pin every time the stockings of the wearer are removed is obviated.

I attain these ends by a novel construction of a safety-pin coacting with a novel construction of clip or clasp and its adjuncts which can be readily attached to or disconnected from a member of said safety-pin, according to requirements.

My invention further consists of the novel combination of a safety-pin, clip, slide, and their adjuncts, all as will be hereinafter fully set forth, and pointed out in the claims.

Figure 1 represents a plan view of my improved stocking-supporter embodying my invention. Fig. 2 represents a section on line xx , Fig. 1. Fig. 3 represents a plan view of certain of the parts seen in Fig. 1, but in disconnected position.

Similar numerals of reference indicate corresponding parts in the figures.

Referring to the drawings, 1 designates a safety-pin which is provided with an offset or deflected portion 2, which is engaged by the hook 3, which forms a continuation of the back 4 of the clip 5, which is provided with the spring-tongue 6, having the swell or bulged portion 7, the upper extremity of said tongue 6 normally being in contact with the under surface of the hook 3.

8 designates a slide which has an upper member 9 passing through an eye 10 in the lower portion of the clip 5, said slide having slots 11 and 12, through which the upper end 13 of the strap 14 is passed, said main strap 14 having branches 15 and 16, which are provided at the lower ends with clasps 17 of any suitable or approved form, whereby they may be secured to the top of the stocking. The branches 15 and 16 may be in one piece folded and sewed or otherwise attached to the main strap 14, or one of the branches may be an extension of said strap, the other being sewed or otherwise attached to it. If desired, all these parts may be sewed or otherwise woven in one piece.

The operation is as follows: The safety-pin 1, which is secured, preferably, to the under side of the corset of the wearer, and its adjuncts appear in assembled position, as seen in Fig. 1, the clasps 17 being attached to the stocking in the usual manner. When it is desired to remove the stocking, it is only necessary to disconnect the hook 3 from the member 2 of the safety-pin by depressing the spring-tongue 6, said safety-pin remaining attached to the corset of the wearer, the parts 5, 14, 15, and 16 being removed in unison with the stocking.

I desire to direct special attention to the feature of providing for the ready disconnection of the clip 5 from the safety-pin, since the necessity of fastening and unfastening the safety-pin whenever the stocking is removed is avoided, as is also any danger of injuring the fingers or finger-nails in the frequent unfastening of the safety-pin, which is a feature of great importance.

It will be apparent that changes may be made in the manner of assembling the safety-pin, spring-clips, and their adjuncts which will come within the scope of my invention,

and I do not, therefore, desire to be limited in every instance to the exact construction I have herein shown and described.

Having thus described my invention, what I claim as new, and desire to secure by Letters Patent, is—

1. In a stocking-supporter, the combination of a main strap and the branches connected thereto, a safety-pin extending transversely to said main strap and a detachable clip secured to a slide carrying said main strap and removably connected to the lower member of said safety-pin, whereby the latter may be permanently attached to the corset of the wearer during the disconnection of said clip therefrom.

2. A stocking-supporter consisting of a main strap and the branches connected thereto provided with clasps at their lower portions, a slotted slide, through which the upper end of the main strap passes, a spring-clip attached to said slide and a safety-pin having a deflected member extending trans-

versely to said main strap, said clip being detachably connected to said safety-pin, whereby the latter may be permanently attached to the corset of the wearer during the disconnection of said clip therefrom.

3. A stocking-supporter consisting of a main strap having the branches connected thereto and provided with clasps at their lower portions, a slotted slide, having an upper extremity of said main strap passing therethrough, a spring-clip secured to said slide, and having a hook on its upper portion, and a safety-pin extending transversely to said clip and having a deflected member adapted to detachably engage said clip, whereby the latter may be permanently attached to the corset of the wearer during the disconnection of said clip therefrom.
